 Western Electric Company, Incorporated, New
 York, N. Y., a corporation of New York

Application March 23, 1943, Serial No. 480,169

4 Claims. (Cl. 248—124)

1

This invention relates to an adjustment fixture and more particularly to a device for holding an article to be operated on in predetermined relation to means for illuminating and inspecting the article.

There are many instances in various arts where an article composed of a plurality of components needs to have minor adjustments of its component elements relatively to each other made after assembly of the article before the article is satisfactorily usable for its intended purpose. Thus, certain vacuum tubes for use in the electrical arts have a double, concentric grid, i. e. a pair of flattened helices of wire of the same pitch, of which one is within the other and both are mechanically supported on a common base by means of separate pairs of posts. For some uses, it is important that each half turn of the wire of one helix lie accurately parallel to the corresponding half turn of the other helix and in a plane perpendicular to the common plane of the four posts of the two helices.

An object of the present invention is to provide a device or adjustment fixture to hold an article in predetermined relation to a predetermined line of sight and to a means of illumination, and having means to change the position of the article in predetermined fashion with respect to the line of sight.

With the above and other objects in view, the invention may be embodied in a device or fixture having means to determine a line of sight, a support to receive and hold an article in the line of sight, means to illuminate the face of the article facing the line of sight, means to adjustably traverse the support perpendicularly to the line of sight, and means to rotate the support about an axis perpendicular to the line of sight.

Other objects and features of the invention will appear from the following detailed description of one embodiment thereof taken in connection with the accompanying drawing in which the same reference numerals are applied to identical parts in the several figures, and in which

Fig. 1 is a view in perspective of a double grid adjustment fixture constructed in accordance with the invention;

Fig. 2 is a detached, enlarged, central, vertical section through the lens and first screen;

Fig. 3 is a detached, enlarged, section through the grid support traversing means and rotating means, transverse to the line of sight;

Fig. 4 is a section through the showing of Fig. 3 and at right angles thereto;

2

Fig. 5 is a front elevation of a double grid to be held in the fixture;

Fig. 6 is a section on the line 6—6 of Fig. 5;

Fig. 7 is a plan view of the left end of the showing of Fig. 3 with the grid assembly removed, and

Fig. 8 is a front elevation of the showing of Fig. 7.

The apparatus herein disclosed as an illustrative embodiment of the invention, is a fixture for holding and inspecting a double concentric grid intended to be used in vacuum tubes, while the turns of the helices of the grid are being manually adjusted to mutual parallelism. To make the nature, purpose and scope of the invention as illustrated in this particular embodiment more easily apprehended, the grid assembly, which is no part of the invention, will be described first so far as relevant to the invention.

The grid assembly, for which the device of the invention is primarily designed, is shown by itself, in one specific form only, in Figs. 5 and 6. It comprises a pair of identically similar bases 10 and 11 of insulating material, preferably ceramic, in which are mounted, in a central plane, longitudinal of the unit as a whole and transverse to the bases 10 and 11, four metal members 12, which will be the plate of the vacuum tube, and two pairs of metal rod grid supports 14, 15 and 16, 17 respectively. The two rods of each pair are on opposite sides of the plate members 12 and coplanar with these, the pair 14, 15 being also outside of the pair 16, 17. The plate members 12 terminate, hold together, and space apart the bases 10 and 11. The grid supports 14, 15, 16 and 17 pass through and extend beyond the outer faces of the bases. The plate members are electrically interconnected by means not visible in the figures and also to terminals 13 mounted on the under face of the base 10. Elastic, laminar, contact fins 18 are mounted on the bottom ends of the rods 14, 15, 16 and 17.

The rod-shaped grid supports 14, 15, 16 and 17 are each provided on their outer sides with suitably spaced and located notches 19, 20, 21 and 22 respectively, to hold and support the consecutive coils or turns of two flat helices 25 and 26 of wire. The supports are so held in the bases and the notches in the supports are so spaced and located that to each notch 21 corresponds a notch 19 at the same distance from the base 10, and to each notch 22 similarly corresponds a notch 20, except for the two uppermost and one lowermost notches 21 and 22 for which there are no correspondent notches.

The notches are further so located and spaced

that a wire 23 wound in the notches 19 and 20 and a wire 24 wound in the notches 21 and 22 in the manner shown, form the two helices 25 and 26 respectively, whose respective half turns are to run parallel each to each in planes perpendicular to the plane of the plate members 12. The article thus described when first assembled, will have the corresponding coils of the two helices approximately in the desired positions relatively to each other and to the axial plane of the whole. The problem then arises of how to hold and manipulate this assembly safely and conveniently, while each half turn of one or the other helix is adjusted to run parallel to its correspondent in the other helix and with the common plane of the two at right angles to the axial plane of the assembly.

This is the purpose and function of the device or fixture shown in Figs. 1 to 4 inclusive. This fixture comprises a main base 30, either heavy enough in itself to give stability to the whole or to be secured or clamped on a bench or table. Upon this is mounted a tiltably adjustable, plate-like base 31. An upstanding, transverse wall member 32 is rigidly secured on the base 31. Near the upper edge of the wall 32, two parallel tubular supports 33, 33 are rigidly mounted in the wall, extending therethrough at right angles thereto. Support rods 34, 34 are slidably adjustable in the tubes 33 and may be clamped in adjusted position by means of clamp screws 35, 35. A depending laminar screen or optical diaphragm 36 is rigidly supported on the forward ends of the tubes 33 and is formed with a transverse slot 37. On the forward ends of the rods 34 is mounted a depending, transverse housing 38 in which is a laminar screen or optical diaphragm 39 formed to fit over the front surface of a magnifying lens 40 also held in the housing 38. The screen 39 has a transverse slot 41. An eye shade 42 may be mounted on the forward side of the housing 38 if desired. The front faces of the wall 32, screen 36 and screen 39 are preferably made matt black by being suitably painted or otherwise.

Between the wall 32 and the screen 36, a grid assembly support block 43 is mounted on a rack 44 to be pivotable about an axis in the line of reciprocation of the rack. The rack is reciprocable up and down in a pedestal 45 rigid on the base 31 and is engaged by a pinion 46 on a shaft 47 journalled in the pedestal 45. Means as indicated at 48 are provided to supply sufficient frictional resistance to the rotation of the shaft 47 to prevent the weight of the members mounted on the rack from moving the latter down and, in general, to prevent motion of the rack and of the block 43 up or down, unless the shaft 47 is intentionally rotated by one of the knurled heads 49, 49. Means as indicated by the spring pressed ball 50 acting on corresponding indentations 51 in the integral pivot formed on the rack, to maintain the block 43 yieldingly in either of two positions 180° apart. The block 43 is formed on its upper side with a groove or slot 52 to act as clearance space for the parts of a grid assembly which project below the assembly base 10 when the assembly is placed on the block 43 in the position indicated in the first four figures.

To positively locate the grid assembly in an accurately predetermined position on the block 43, there is provided a positioning member 53 mounted on the block 43 across one end of the slot 52. The thickness of the member 53 is the same as that of the grid assembly base 10. The member 53 is formed with locating means such as fingers 54, 54 to fit into and engage correspond-

ing means on the base 10, e. g. the recesses 55, 55, and so to locate the base 10 on the block 43 in an accurately predetermined relative position. To hold the grid assembly removably in this position clip springs 56, 56 are provided to frictionally engage the base 10.

Along one up and down edge of the screen 36 and behind the screen is positioned an elongated light source, e. g. a fluorescent lamp 57 in tubular form, fed with electric current from any convenient source, not shown. Such a light source will illuminate the front side of a grid assembly, mounted on the block 43 as indicated in Fig. 1, in a substantially shadowless and glareless manner, as seen through the slot 41, lens 40, and slot 37, making accurate inspection of the grid wires easy and not tiring to the eyes, since the light falls on the horizontally disposed wires over a considerable angle from well below the line of sight to well above it. Hence, each wire visible in the field of vision is substantially equally illuminated over a portion of its periphery greater than the visible portion. To ensure this, as well as to concentrate attention on the particular pair of wires to be adjusted, the slots 41 and 37 are so dimensioned that with the forehead against the eye shade 42 and the rack 44 suitably elevated, the particular pair of wires in question will lie horizontally and one behind the other across the middle of the elongated narrow horizontal field of view, preferably with a few but only a few of the neighboring pairs above and below also in sight. If the slots be narrow enough to limit the field to a single pair of wires, diffraction disturbances are apt to produce eyestrain, darkening of the field and indistinctness. A convenient basic factor is to select the lens 40 with a focal length of 6 to 12 inches, preferably about 9 inches, and dimension the rest of the apparatus to correspond. The distance of the lens 40 from a grid assembly on the block 43 is made adjustable at 35, 35, to adjust this to the requirements of different eyes.

Since the grid wires to be adjusted relatively to each other lie in different planes transverse to the optical axis of the device, i. e. at different distances from the eyes, it is practically necessary to have the apparatus arranged for binocular vision as otherwise it would be difficult, or even impossible, for the operator to be visually certain which of two grid wires under simultaneous observation stands in front of the other. Hence is derived the peculiar value of the slotted diaphragms defining the horizontally elongated and vertically limited field of vision.

With the apparatus as shown in Fig. 1 and a grid assembly in place on the block 43 and the block in its lowest position, the front half of the top coil or turn of the outer helix 25 should be at or below the horizontal center line of the field of view. If it is below the center, the half turn is brought up to the center by turning one of the knurled heads 49. The corresponding front half turn of the inner helix 26 should then be invisible over its whole length behind the half turn of the outer helix 25. If it is not, the operator, with a pair of tweezers or other suitable implement, will bend one or the other or both half turns of the pair until this condition exists. A head 49 is then turned to bring the next pair of front half turns to the center of the field and these are corrected if necessary. This is repeated until the whole front side of the assembly has been inspected and corrected if necessary, coil by 70 coil. The block 43 is then rotated, forcing the

spring latch 50 out, until it catches again 180° away. The rear side of the assembly is then presented for inspection with the bottom pair of corresponding half turns nearly in position in the field of view. The rear turns are preferably inspected from bottom to top in same manner that the front turns were inspected from top to bottom. The operator will not then forget to inspect both sides, knowing that when a piece of work is all the way up, it is only half done.

It will be noted that the apparatus as described combines, as basic components, an optical system comprising the lens 40 and the screens or optical diaphragms 36 and 38, together with the article support means which is capable of being adjusted to traverse an article thereon across the optical axis of the optical system and also to rotate the support and article, independently of the traversing motion, about an axis perpendicular to the optical axis, into two predetermined positions 180° apart in either of which the support is yieldingly locked. The number of positions thus provided for, is two in the particular embodiment chosen to illustrate the invention, because the grid assembly to be dealt with has two aspects to be considered. In other instances the article in question might have three or four or even more aspects, in which case a corresponding number of indentations 51 to receive the ball latch 50 would be provided.

The invention has been illustrated as embodied in an apparatus for holding a particular grid assembly in and adjustably moving it across an illuminated, limited field of view to facilitate inspection and adjustment of correlated turns of windings; but the invention is believed not to be so limited. Modifications and variations to adapt it to other types of articles to be examined are believed to be obvious to those skilled in the art and to come within the spirit and scope of the invention as particularly described and pointed out in the appended claims.

What is claimed is:

1. In an optical device for observing and holding articles to be adjusted and having an optical system for observing an article, a support base

rigidly mounted beside and spaced from the optical axis of the system, a support carrier mounted in the support base to be adjustably traversable therein toward and from the optical axis at right angles thereto, and an article support mounted on the carrier to be rotatable thereon about the axis of motion thereof with respect to the support base.

2. In an optical device for observing and holding articles to be adjusted and having an optical system for observing an article, a support base rigidly mounted beside and spaced from the optical axis of the system, a support carrier mounted in the support base to be adjustably traversable therein toward and from the optical axis at right angles thereto, and an article support mounted on the carrier to be rotatable thereon about the axis of motion thereof with respect to the support base, together with means to yieldingly lock the article support on the carrier in either of two angularly spaced positions thereon.

3. In an optical device for observing and holding articles to be adjusted and having an optical system for observing an article, a support base rigidly mounted beside and spaced from the optical axis of the system, a pinion mounted in the support base, a rack housed in the support base and engaging the pinion to be traversable thereby toward and from the optical axis at right angles thereto, and an article support pivoted on the rack to be rotatable thereon about the axis of motion thereof.

4. In an optical device for observing and holding articles to be adjusted and having an optical system for observing an article, a support base rigidly mounted beside and spaced from the optical axis of the system, a pinion mounted in the support base, a rack housed in the support base and engaging the pinion to be traversable thereby toward and from the optical axis at right angles thereto, and an article support pivoted on the rack to be rotatable thereon about the axis of motion thereof, together with means to yieldingly lock the article support on the carrier in either of two angularly spaced positions thereon.

VINCENT G. JARMAN.
